UNITED STATES PATENT OFFICE.

ALPHONS L. WESTRICH, OF HAWTHORNE, CALIFORNIA.

WALL CONSTRUCTION.

Application filed June 8, 1927. Serial No. 197,466.

My invention is a wall construction made of tiles, blocks, bricks or the like.

An object of my invention is a wall construction made of tiles, block or bricks, each 5 tile being formed angular or somewhat L-shaped in cross section and the blocks interfitting, forming opposite faces or sides of the wall.

Another object of my invention is the 10 construction of a wall with blocks or tiles substantially L-shaped in cross section, the long arm of the L or angle forming the outside face of the wall and the short arm interengaging with blocks, forming the other 15 or opposite face of the wall. A further object of my invention is to form the wall construction with blocks as above described, thereby giving an air space between the two faces of the wall.

20 A further object of my invention is a block or tile for wall construction formed somewhat L-shaped in cross section, the short arm forming a transverse part of the block and having a cut-out section. The 25 blocks are also formed with corrugations on the edges, which interfit with adjacent blocks.

Another object of my invention is the 30 construction of a mold for forming the blocks, and the method of molding.

My invention will be more readily understood from the following description and drawings, in which:

Figure 1 is a perspective view of a wall 35 constructed in accordance with my invention.

Figure 2 is a vertical transverse section on the line 2—2 of Figure 1, in the direction of the arrows.

40 Figure 3 is a vertical longitudinal section of part of the wall on the line 3—3 of Fig. 2, in the direction of the arrows.

Figure 4 is a perspective view of one of the blocks.

45 Figure 5 is a plan view of the mold for forming the blocks.

Figure 6 is a longitudinal section through the mold on the line 6—6 of Fig. 5, in the direction of the arrows.

50 The particular block or tile forming a feature of my invention is substantially as follows, being designated generally by the numeral 11:

This tile is formed angular or L-shaped 55 and has one arm 12 forming a long arm, and another arm 13 forming a transverse arm.

The end edge 14 of the long arm is preferably corrugated with longitudinal corrugations, and the end face 15 of the short arm 13 is also preferably corrugated with longitudinal corrugations. The L-shaped arm 13 has a recessed or cut-out section 16 forming in effect lugs 17 at each end of the block on the short arm. The flat face 18 of the block, being the side of the long arm, forms the 65 outside face or finished side of the block.

The side face 19 of the arm 13 forms an inside face of the block as does also the side 20 of the long arm 12. The block is so constructed that the measurement 21 from the 70 lower edge 15 to the upper surface of the lug 17 is one-half the measurement 22 between the edges 14 and 15. The lugs 17 may extend any desired distance from the end of the block.

75 The manner of building up a wall in accordance with my invention is substantially as follows:

Having reference particularly to Figures 1, 2 and 3, in which case a lower block 23 is 80 formed by breaking a complete block at the level of the top of the lug 17, or by forming a special block. Adjacent thereto, an opposite block 24 is constructed on a base or foundation 25 with edge 14 downwardly and the edge 15 up, with the face 18 forming a finished face of the wall. The short arm 13 of this block overlaps the edge 15 of the block 23, these blocks being set apart so that there is a space 26 between the blocks. Another complete block 27 is built up on the other side of the wall, the edge 14 fitting on the edge 15 of the block 23 and with the face 18 outwardly. This block has the lugs 17 substantially engaging the edge 15 of the block 24, leaving a space 28. The meeting and joining edges of the blocks are secured by ordinary mortar or by cement mortar, and, if desired, longitudinal re-enforcing bars 29 may be imbedded in the mortar, 100 preferably the layer of mortar on top of the edge 15 of each of the blocks. By this construction, a zigzag air passage 30 is formed between the blocks forming the two sides of the wall, this zigzag passage being formed 105 by the space sections 26 and 28 between the blocks and the space left by the recessed or cut-out section 16 of the short arm 13 of the block. The blocks are preferably built up to break joint as shown in Fig. 1, which shows the recess 16 as forming a part of the air space in a transverse direction, the spaces

26 and 28 forming the air space in a vertical direction.

If desired, the wall may be built up by starting the blocks with the lower edge 15 downwardly and the narrow edge 15 upwardly, and continuing the wall upwardly in this manner, the blocks being preferably off-set to form the spaces above mentioned, where it is desired to form a wall with air space between the two sides. If a solid wall is desired, these spaces between the blocks may be filled with cement or the like, with or without re-enforcement, and if desired the blocks may be placed close together so that the inside surface 19 of the blocks on one side of the wall substantially contact with the surface 20 of the blocks on the other side of the wall, and mortar may be placed between these two surfaces forming an additional binding of the wall. The blocks may also be built up forming any suitable type of joints, either broken as illustrated in Fig. 1, or in any of the various types of joints used in brick work or in block or tile construction.

The mold for making the blocks is constructed substantially as follows:

As illustrated in Figures 5 and 6, there are a pair of opposite side-boards 35 and a plurality of full height transverse boards 36 and a plurality of substantially half height boards 37. Blocks 38 are fitted between and secured to boards 36 and 37, and bolts 39 may be utilized to secure the assembly comprising the boards 36, 37 and the blocks 38, to the side-boards 35. Strips of sheet metal such as galvanized iron 40 are secured to the upper edge 41 of the half height boards 37 and to the upper edge 42 of the blocks 38, the side edge 43 of this metal strip abuts against the side of each of the boards 36. The boards 36 are completely corrugated on one side 44 and are partly corrugated on the other side, as indicated at 45. The outside surface 46 of the half height boards 37 is also corrugated.

The recessed or cut-out section 16 of the blocks is formed by inserting wood fillers, or the like, 47, which preferably have a beveled end 48, in the space between the sides 44 of the boards 36 and the sides 46 of the boards 36. Covering part of such latter boards, a strip of fabric 49 or other suitable material is secured to the fillers 47 and extends over the sheet metal strip or covering 40. The whole mold as built up is supported on a base 50.

The manner of molding the blocks is substantially as follows:

When the mold is assembled as above described, it is preferably coated with some material which will prevent adherence of concrete or cement, such as by a coating of kerosene or some light oil, and the cement is molded in the open space and, if desired,

is tamped against the base 50 and into the corrugations on the mold boards, until the mold is filled to the level of the upper edge of the boards 35 and 36. The form is then allowed to set for the desired length of time, keeping the cement tempered by moistening in the usual manner.

It is not necessary that all of the mold sections be secured by bolts 39, as these can be spaced the desired distance apart and the friction holds them in place when the cement is molded in the proper manner in order not to disturb the spacing. However, there should be a sufficient number of these bolts to hold the assembly in a solid position. These bolts may be disconnected and the side-boards 35 removed, then the mold parts, starting at one end, can be removed one at a time, the blocks taken out and the filler pieces 47 disconnected from the blocks, leaving a finished cement block substantially as shown in Fig. 4.

From the above description, it will be seen that I have developed a novel type of block which may be utilized to make a wall construction as illustrated in Figures 1 and 2, with the angular or L-shaped blocks interfitting from opposite sides of the wall; and this construction may be utilized to make a hollow or solid wall, as desired. I have also developed a mold suitable for making such blocks, the method of molding blocks having the above characteristics. It is to be understood that the blocks may be made in any suitable manner and if desired these may be of a clay product molded by suitable machinery and burnt in kilns, or the like.

Various changes may be made in the principles of my invention without departing from the spirit thereof, as set forth in the description, drawings and claims.

I claim:

1. A building block substantially L-shaped in cross section, one arm of the L having a cut-out section adjacent the inner angle of the L with lugs at each end of such arm, the thickness of such arm at the lugs being substantially half that of the width of the other arm, and the said block having corrugated upper and lower edges.

2. A wall construction comprising in combination a plurality of L-shaped blocks, each block having an arm forming part of the wall face, one edge of said arm being corrugated, the other arm of the L forming a transverse part of the wall and having a cut-out section between end lugs, the thickness of the transverse arm at the lugs being substantially half the width of the face arm and said transverse arm having corrugations opposite the said corrugated edge, and cementing material binding the blocks.

3. A building block of general L-shaped section defined as having a vertical branch of the L and a horizontal branch, the hori-

zontal branch having horizontal lugs at each end and a depressed or cut-out section having a horizontal top surface, the vertical measurement of the horizontal branch through the lugs being substantially half that of the vertical branch.

4. A building block substantially L-shaped in cross-section defined as having a vertical branch with ribs on the top horizontal surface and a horizontal branch with ribs on the lower horizontal surface, said horizontal

branch having lugs at each end with grooves on the top horizontal surface and having a cut-out or depressed section with a horizontal surface between the lugs, the vertical height of the horizontal branch through the lugs being substantially half that of the vertical branch.

In testimony whereof I have signed my name to this specification.

A. L. WESTRICH.
